RICHARD W. F. ABBE, OF NEW YORK, N. Y.

RECORDING-COMPASS AND MARINE INDICATOR.

SPECIFICATION forming part of Letters Patent No. 363,039, dated May 17, 1887.

Application filed December 26, 1885. Serial No. 186,748. (No model.)

To all whom it may concern:

Be it known that I, RICHARD W. F. ABBE, of the city, county, and State of New York, have invented a new and Improved Marine Indicator, of which the following is a full, 5 clear, and exact description.

The object of my invention is to provide a new and improved marine indicator for vessels for automatically indicating the speed of the 10 vessel, the leeway, the direction of sailing, and to furnish a complete and reliable record of such speed, direction of sailing, course of the vessel, &c.

The invention consists in parts and details 15 and combinations of the same, as will be fully described and set forth hereinafter, and then pointed out in the claims.

Reference is to be had to the accompanying drawings, forming a part of this specification, 20 in which similar letters of reference indicate corresponding parts in all the figures.

Figure 1 is a cross-sectional elevation of my improved indicator on the line *x x*, Fig. 2, parts being broken out. Fig. 2 is a sectional 25 view of the same on the line *y y*, Fig. 1, parts being broken out. Fig. 3 is a longitudinal, sectional elevation of part of a vessel, showing the manner in which my improved marine indicator and the devices for operating the 30 same are placed in the vessel. Fig. 4 is an enlarged detail sectional view of the driving mechanism of my improved marine indicator, parts being broken out. Fig. 5 is an enlarged detail sectional view of the belt-shifter. Fig. 35 6 is a diagram illustrating the operation of my improved indicator. Fig. 7 is a detail view of the parts on the lower end of the tube.

The cup-shaped vessel *A*, preferably made of sheet metal, is provided with a rim, *A'*, which is suspended by means of hangers *A''* from a ring, *A''*, pivoted at points at right angles to those at which the rim *A'* is suspended from said ring to a box, *B*, which is pivoted by pivots *B' B''* to a box, *C*, the pivots *B' B''* being diametrically opposite the pivots *A''*, by which the rim *A'* is pivoted in the box *B*. The said cup-shaped vessel *A* is provided with a top plate, *D*, secured in the rim *A'* and provided at its middle with an upwardly-projecting neck, *D'*, through which the stem *D''* projects from the center of a card, *D''*, which is in the vessel *A* below the top plate, *D*, and is mounted to revolve on the pointed pivot *D'*, projecting upward from the bottom of the vessel *A*, the card being provided at its center with a recess or cavity in the under side for receiving the point of the pivot *D'*. The card *D''* carries the permanent magnet *D''*, which may be composed of a single U-shaped piece of steel, or a series of steel wires bunched together. The vessel *A* is filled with glycerine or a like liquid, which extends almost to the top of the neck *D'* on the plate *D*.

On the top of the stem *D''* on the card *D''* a circular plate, *E*, is secured above the neck *D'*, and on the said plate a series of type-levers, *E'*, are pivoted to project radially from the same, each lever carrying on its outer end and upper edge a type-block, *E''*, there being as many type-levers as there are points of the compass, the several type-levers being marked with letters corresponding to the letters on the compass-card *D''*, above which they are located. An endless inked band, *E''*, such as is used in type-writers or hand-stamps, is passed over two pulleys, *E''*, mounted on shafts *F''*, operated by a clock-work. The ends of the type-levers *E'* can pass under the upper part of said inking-band. The clock-work *F* is held on the ring *A''*, connected with the vessel *A* by the hangers *A''*, and operates a hammer, *F'*, which is located below the upper part of the inking-band in such a manner that it can strike upward and against the under side of the type-levers *E'* and press the type-blocks *E''* on the same against the band, thereby pressing the inked band against a strip of paper, *G*, which is unwound from a coil, *G'*, mounted on a spindle, *G''*, resting on the bottoms of the slots *G''* in standards *G''* on cross-pieces *A''* of the ring *A''*. From the said coil *G'* the paper is passed over the roller *F''*, directly above the inking-band *E''*, and then half-way around the roller *F''*, then over a roller, *F''*, on arms *G''* of the standards *G''*, and is finally wound on the reel or drum *G''*, and forms the paper-roll *G''*, said drum or reel *G''* having pivots which are passed into the slots *G''* of the standards *G''*. The roll *G''* of paper rests upon the roll *G'*, and is revolved from the same by frictional contact.

The pulley *F''* is mounted on the same shaft,

H, with the cone-pulley H', over which a driving belt or cord, H², passes, which also passes over the sliding forks H³, mounted to slide in the longitudinal grooves H⁴ in the cone-pulley 5 H⁵, which is the reverse of the cone-pulley H'. The forks H³ have their inner ends made T-shaped or dovetailed, so that they cannot be moved out of their grooves in the cone-pulley, and are connected with the rods H⁶, which 10 in turn are pivoted to the nut H⁷, mounted to turn on the screw-threaded part H⁸ of the shaft I, on which the cone-pulley H⁵ is rigidly mounted, said nut H⁷ being provided with a handle, H⁹, whereby by turning said handle 15 the nut is turned and moved toward or from the base end of the cone-pulley H⁵, and thus the forks H³, over which the cord or belt H² is passed, are moved toward or from the base of the cone-pulley H⁵, whereby the speed with 20 which the cone-pulley H' is revolved from the pulley H⁵ can be increased or decreased. The other pulley is provided with a like belt-shifting device.

On the shaft I a grooved pulley, I', is 25 mounted, over which the driving cord or belt I² is passed, which is also passed over the grooved driving-pulley I³ on one end of the shaft J, journaled in the standards J' in the bottom of the box B.

30 The shaft J is provided at its opposite end with a rigidly-mounted worm-wheel, J², engaging with a worm, J³, formed on the shaft J', journaled in the lower part of the box B, and provided on the end outside of the box with 35 the grooved pulley J⁵, over which the endless driving cord or chain J is passed, which is also passed over a pulley, J⁶, mounted loosely on the pivot B² of the box B, and connected with the grooved pulley J⁵, over which a driving cord or chain, K, passes, which is also 40 passed over the grooved pulley K' on the end of a shaft, K², journaled in the box C and in the standard K³ on the upper surface of the bottom of the box C, said shaft K² carrying 45 the beveled cog-wheel K⁴, engaging with the beveled cog-wheel K⁵ on the upper end of a vertical shaft, K⁶, that is passed down through the bottom of the box C.

To the under side of the box C the tube C' is secured, which extends downward through a vertical tube, L, in the vessel to below the keel, said tube C' being formed of sections which can be screwed together. The tube C' is provided at its top with a flange, on prongs 55 of which rollers C² are pivoted to run on the platform or table C'.

Through the tube C' the shaft M passes, which is provided at its upper end with a square aperture for receiving the lower 60 squared or pointed end of the shaft K⁶, above mentioned, which shaft K⁶ is provided with a transverse piece, K⁷, carrying rollers K⁸, which run on the top of the flattened head or flange of the tube C'. The tube C' is provided at suitable intervals—that is, at the screw-joints—with necks C⁹, in which the shaft M can revolve. On the lower end of the tube C' a collar, L', is

fixed, in which rollers L² are pivoted, which run on the inner surface of the tube L. On the lower end of the tube C' the forked piece N⁸ is secured, between the prongs of which a metal box, N, is pivoted. To the said forked piece N⁸ a vane-rod, N', is pivoted, which is formed of a series of rods jointed by joints N², which are so constructed as to permit the vane-rod to 75 be folded very compactly. Said rod must be about thirty feet long.

From the opposite end of the box N a shaft projects, on which a screw or other water-motor, P, is mounted, said propeller P being 80 mounted in a frame, O, the inner ends of which abut against the front edges of the forked piece N⁸, and to the said frame O a hanger, O', is pivoted, which is secured to the lower end of a rope or chain, O², passed over a 85 pulley, O³, in the lower part of the collar L', through the aperture O⁴ in said collar, and up through the tube L to a hook, O⁵, to which the upper end of said rope or chain O² can be fastened.

90 The screw P revolves the shaft P', passed through the front of the box N and provided on its end with a worm, P², engaging with a worm-wheel, P³, on a shaft, P⁴, journaled in the box N, which shaft carries the pinion Q, 95 engaging with the cog-wheel Q', mounted on the vertical shaft Q² in the box N and carrying the pinion Q³, engaging with a ratchet-wheel, R, on a vertical shaft, R', provided at its upper end with a squared socket or recess, 100 R², for receiving the lower squared or pointed end, M', of the vertical shaft M. The diameter of the tube L must be greater than the diameter of the propeller P, the forked piece N⁸, or the box N, so that the same can be drawn up 105 or down through the said tube.

T represents the marine vessel, and S the keel of the same.

The operation is as follows: The clock-work F is so constructed that it moves the finger or hammer F' upward at regular intervals—for example, every minute or every two minutes, or, if desired, every five minutes, as the case may be. Every time the finger or hammer F' moves upward it presses the type block E² on 110 that end of the type-lever E' above the hammer against the paper G, passed over the roller F², and thus the impression is made. The compass-card D turns on the pivot D', and thus different type-levers E' will be above the hammer or finger F', according to the direction in 115 which the ship sails, whereby the direction of sailing at the time may be printed on the paper strip. If the same character is printed on the paper strip successively for a number of 120 times, it shows that the ship's course has not been changed. Whenever a change of character takes place on the strip, it shows that the direction of the ship's course has been changed, and the character shows to what direction it 125 has been changed.

In order that the speed of the vessel may be shown on the paper strip, it is necessary that the speed with which the paper strip is passed

over the roller F² corresponds with the speed with which the vessel glides through the water. According as the speed of the vessel increases or decreases, the screw P revolves with 5 greater or less rapidity, and by means of the gearing in the box N revolves the shaft M, which in turn revolves the shaft K⁶, provided with the beveled cog-wheel K⁶, by which the beveled cog-wheel K⁷ and the shaft K² are revolved, and from the same the united pulleys J⁷ and J⁸ and the pulley J⁹ on the shaft J⁴ are revolved, and from said shaft J⁴ the shaft J is revolved by means of the worm J³ and the worm-wheel J², and from the shaft J the shaft 10 I is revolved by means of the driving cord or chain I². From said shaft I the pulley F³ is revolved by means of the belt H², as said pulley is on the same shaft with the cone-pulley H¹. By the revolution of the pulley F³ the paper 15 G is unwound from the roll G¹, which is revolved in the direction indicated by its arrow, and as the roll G¹ rests upon the roll G² and is in frictional contact with the same, the roll G¹ will be revolved in the direction of its arrow, Fig. 1, and the printed part of the paper 20 is wound on the roll G¹, the diameter of which increases as the diameter of the roll G² decreases. As the pivots of the rolls G¹ and G² are in the vertical slots of the standards G⁴, said pivots can slide up and down, as 25 is necessary to keep the rolls in contact. When the ship is sailing due north, as shown in Fig. 6, and the vessel is carried by the current in the direction of the dotted arrow, Fig. 30 6, the vane-rod N' will project from the side of the vessel, as indicated in Fig. 6, and will be on line with the direction in which the ship is carried by the current, which is indicated by the dotted arrow. As the vane-rod swings 35 in said direction it turns the tube C', whereby the box C is turned on its table, and thus the leeway of the vessel is shown. 40

When the indicator is not to be used on the vessel, the box C is first removed from the upper end of the tube C', and then the upper end of the rope or chain O² is disengaged from the hook O⁶ to permit the frame O, in which the propeller P is journaled, to swing down. As 45 soon as the vessel stops the pointed vane-rod N' also swings down, and then the box N and the parts on the lower end of the tube C' can be drawn up through the tube L. The indicator can thus be adjusted for use or removed very easily and rapidly whenever this is necessary. 50

I do not limit myself to the exact construction of the parts herein shown and described for driving the mechanism for winding the strip of paper, as the same may be varied more or less, as circumstances may require. 55

As the impressions on the paper strip will be a greater distance apart when the ship sails rapidly than when it sails slowly, the speed of the vessel is clearly indicated on the strip. 60

A true record of the entire voyage of the vessel is thus kept by the marine indicator, as it shows every variation in the course and

the speed during the entire trip. This is of the greatest importance, especially in case of collision or when vessels run out of their course, as the record kept by the apparatus cannot be changed, is absolutely reliable, and is more valuable for establishing facts than the testimony of officers, crew, or passengers. 70

Having thus fully described my invention, 75 I claim as new and desire to secure by Letters Patent—

1. A ship's compass provided with an automatic recording device, arranged to print characters or signs indicating the course of the vessel at intervals corresponding to the speed of the same, substantially as set forth. 80

2. A ship's compass provided with a recording device operated from on board and a paper-shifting mechanism operated from devices in the water, substantially as shown and described. 85

3. A ship's compass provided with a recording device operated by clock-work and a paper-shifting mechanism actuated by the motion of the vessel, substantially as shown and described. 90

4. A ship's compass provided with type-levers corresponding in number to the points of the compass-card and a mechanism operated by clock-work and arranged to press against a strip of paper that type-lever corresponding to the course of the vessel, substantially as shown and described. 95

5. A ship's compass provided with type-levers corresponding in number to the points of the compass-card, clock-work, and a finger or hammer operated by the clock-work for the purpose of pressing against a strip of paper that type-lever corresponding to the course of the vessel, substantially as shown and described. 100

6. A ship's compass having the compass-card steadied by immersion in mercury or a similar fluid and provided with an automatic recording device indicating the positions of said card with respect to the compass box, substantially as herein shown and described. 110

7. A ship's compass having type-levers corresponding in number and denotation to the points of the compass-card, pivoted to a part connected with said card, and provided with a hammer operated by clock-work and arranged to strike at intervals that type-lever corresponding to the course of the vessel, substantially as shown and described. 115

8. A ship's compass having its card provided with an upward projection, on which type-levers corresponding in number to the points of the compass-card are pivoted, substantially as shown and described. 120

9. The combination, with a ship's compass having pivoted type-levers, of a clock-work for operating the type-levers, an inking-band, and a paper-shifting mechanism actuated by the motion of the vessel, substantially as shown and described. 125

10. The combination, with the vessel A, having a top, D, provided with the neck D', of the

- compass-card D³, mounted on a pivot within the vessel A and below the cover, which card is provided with an upwardly-projecting stem passed through the neck of the cover, a magnet 5 on the compass-card, type-levers pivoted on the top of the stem, and mechanism for operating the type-levers, substantially as herein shown and described.
11. The combination, with the vessel A, provided with the cover D, having the neck D', of the compass-card D³, pivoted on a pivot in the vessel and provided with a stem, D², passed up through the neck D', a magnet on said card, type-levers pivoted on the upper end of the stem, an inking-band, mechanism for operating the type-levers, and rollers over which the strip of paper can be passed, which rollers are above the inking-band, substantially as herein shown and described.
12. The combination, with the vessel A, of a compass-card mounted on a pivot in the same, type-levers, corresponding in number to the points of the compass-card, on said card, mechanism for operating that type-lever corresponding to the course of the vessel at any time, a paper-carrier, and a frame on the vessel, in which frame the mechanism for operating the type-levers and the paper-carrier are secured, substantially as herein shown and described.
13. The combination, with the pivoted box B, of the vessel A, pivoted in the same, a compass-card mounted on a pivot in the vessel A, pivoted type-levers on the compass-card corresponding in number to the points of the same, 35 clock-work mechanism for pressing at intervals against a strip of paper that type-lever corresponding to the course of the ship or vessel, and paper-shifting mechanism actuated by and in accordance with the vessel's motion, 40 substantially as herein shown and described.
14. The combination, with a box, of a tube projecting downward from said box through the hull of the vessel and mounted to revolve on its longitudinal axis, a vane on the lower 45 end of said tube below the marine vessel, and a compass in the said box; substantially as herein shown and described.
15. The combination, with a box, of a tube projecting downward from the said box through the hull of the vessel, a vane in the water, mechanism for moving the box from said vane, and a ship's compass in said box, substantially as herein shown and described.
16. The combination, with a table, of a box 55 mounted to turn on the same in the plane of the top of the table, a tube projecting downward from the said box through the hull of the vessel, a vane on the lower end of the said tube, and a ship's compass in said box, substantially 60 as herein shown and described.
17. The combination, with a vane mounted to turn at the bottom of a vessel, of a compass-box turning coincidently with the vane and of a recording device arranged to make impressions indicating the positions of the card in the compass-box with respect to the same, substantially as set forth.
18. The combination, with a tube passed vertically through a vessel, which tube is mounted to turn, of a vane on the lower projecting end of the tube, a box on the upper end of the same, a compass in the box, and printing mechanism arranged to produce characters indicating the positions of the compass-card with respect to the box, substantially as 75 specified.
19. The combination, with a tube passed through a marine vessel and projecting from the bottom of the same, of a jointed vane hinged at the lower end of the tube and a ship's compass on the upper end of the tube, substantially as herein shown and described.
20. The combination, with a marine vessel, of the tube L, passed through and projecting from the bottom of the same, the tube C', 85 mounted to revolve in the tube L, a vane on the lower end of the tube C', and a ship's compass on the upper end of the tube C', substantially as herein shown and described.
21. The combination, with the tube L, passed through a marine vessel to the bottom, of the tube C', mounted to revolve in the tube L and provided at its lower end with a collar, L', which revolves in the tube L, a vane on the lower end of the tube C', and a ship's compass 95 on the upper end, substantially as herein shown and described.
22. The combination, with a tube passed through a marine vessel to the bottom, of the same, of a water-motor on the lower end of the said tube, a shaft in the tube operated by the motor, a paper-winding and a recording device in a box on the upper end of the tube, and mechanism for operating the paper-winding device from the shaft passed through the tube, substantially as herein shown and described.
23. The combination, with a tube passed through a marine vessel to the bottom of the same, of a water-motor provided at the lower end of the tube, a shaft in the tube operated by said motor, a paper-shifting and a recording device in a box on the upper end of the tube, which paper-shifting device is operated by a shaft passed through the tube, substantially as herein shown and described.
24. The combination, with a tube passed through a marine vessel to the bottom, of a water-motor hinged at the lower end of said tube, a rope or chain connected with the said water-motor for the purpose of raising the same and holding it raised, a shaft within the tube operated by the motor, and mechanism driven from the said shaft, substantially as herein shown and described.
25. The combination, with a tube passed through a marine vessel to the bottom of the same, of a water-motor and a vane composed of hinged sections on the lower end of said tube, substantially as herein shown and described.
26. The combination, with a tube passed through a marine vessel to the bottom of the same, of a water-motor and a vane hinged at

the lower end of said tube, substantially as herein shown and described.

27. The combination, with a tube, passed through a marine vessel to the bottom of the same, of a water-motor and a vane hinged at the lower end of the same and a chain or rope for raising the motor and holding it raised, substantially as herein shown and described.

28. The combination, with a tube passed through a marine vessel to the bottom of the same, of a frame hinged on the lower end of the tube, a water-motor in said frame, a shaft in the tube operated from the water-motor, and mechanism on the tube driven from said shaft, substantially as herein shown and described.

29. The combination, with a tube passed through a marine vessel to the bottom of the same, of a box on the lower end of the tube, gearing in said box, a water-motor pivoted on the box and operating said gearing, a shaft passed through the tube and operated by the gearing in the box, and mechanism operated by said tube, substantially as herein shown and described.

30. The combination, with the tube L, passed through a marine vessel to the bottom of the same, of the tube C', passed through and mounted to revolve in the tube L, the collar L' on the lower end of the tube C' and provided with the aperture O', the rope or chain O'', passed through the said aperture and extending up through the tube L, the frame O, pivoted on the lower end of the tube C' and connected with the said rope or chain, a water-motor in said frame, a shaft passed through the tube C' and operated from the water-motor, and mechanism operated from the said shaft in the tube, substantially as herein shown and described.

31. The combination, with a marine vessel, of a tube passed through and projecting from the bottom of the same, a vane secured on the lower end of the tube for the purpose of turning it on its longitudinal axis, a motor on the lower end of the said tube, which motor operates the shaft passed through the tube, a ship's compass on the upper end of the tube, type-levers on the card of the said compass, mech-

anism for operating the type-levers, and a paper-shifting device, which paper-shifting device is operated by motion-transmitting devices from the shaft passed through the above-mentioned tube operated by the water-motor, substantially as herein shown and described.

32. The combination, with a tube passed through a marine vessel to the bottom of the same and mounted to turn on its longitudinal axis, of a vane on the lower end of said tube, a water-motor on the lower end of said tube, a shaft passed through the tube and operated by the water-motor, a box on the upper end of the tube, a ship's compass in the box, type-levers pivoted on the card of said compass, mechanism for operating the type-levers, and a paper-carrier, which paper-carrier is operated by motion-transmitting devices from the shaft passed through the said tube and operated by the water-motor, substantially as herein shown and described.

33. The combination, with a marine vessel, of the tube L, passed through and projecting from the bottom of the same, the tube C', passed through the tube L and mounted to revolve on its longitudinal axis, the forked piece N' on the lower end of the tube C', the box N, pivoted in said forked piece, a vane on the forked piece, a water-motor on the box, a compass on the upper end of the tube C', a printing device on the compass, and a paper-shifting device operated by a shaft passed through the tube C', the said box N, the forked piece N', the motor, and the vane, all being of less diameter than the tube L, so that they can be moved up or down through the same, substantially as herein shown and described.

34. The combination, with a tube passed through a vessel to the bottom of the same and having a forked piece on its lower end, of a box pivoted on the forked piece, a water-motor held on said box, and a vane held on the forked piece, substantially as herein shown and described.
